UNITED STATES PATENT OFFICE

ROBERT H. TOBENER, JR., OF KANSAS CITY, MISSOURI

THROTTLE IGNITION SWITCH

Application filed October 6, 1930. Serial No. 426,702.

My invention relates to switches and more particularly to devices including switches in an ignition circuit for controlling an internal combustion motor, for example the motor operating a vehicle such as a boat, airplane or the like, the principal objects of the invention being to enable the operator of the motor to suspend ignition promptly without requiring access to the motor, and to provide means set by opening movement of a throttle lever, whereby an operator leaving the vehicle may at the same time suspend ignition and close the throttle valve of the motor to reduce damage to the vehicle which might result from continued operation of the motor.

In accomplishing these and other objects of the invention, I have provided improved details of structure, the preferred form of which is illustrated in the accompanying drawing, wherein:

Fig. 1 is a perspective view of my invention as applied to a motor boat shown moving through water, illustrating the device in ignition suspending and throttle closing position, a boatman in the water near by, and a broken line whereby the boatman had conditioned the device for operation.

Fig. 2 is a side elevation of a casing member supporting the operating elements of the device and a throttle lever and throttle operating rod shown fragmentarily, the cover of the casing being removed.

Fig. 3 is a section on the line 3—3, Fig. 2.

Fig. 4 is a diagrammatic view of the wiring system of a motor driven vehicle having battery ignition system and equipped with my invention.

Referring in detail to the drawing:

1 designates a motor boat 2 an internal combustion engine adapted to propel the boat, and having a throttle valve and spark plugs connected to an ignition circuit normally found in engines of this character.

Mounted on one side wall of the boat adjacent the seat for the boatman is a casing including mating body and cover members 3 and 4 comprising plates or side walls having lower edge flanges 5, intermediate ribs or flanges 6, and upper edge flanges 7 forming

a relatively large chamber 8 and a cylindrical channel 9.

The members are held together by bolts 10 with the flanges in close engagement to form the top and bottom walls of the casing, and an intermediate partition.

Pivottally mounted on a pin 11 in the casing adjacent the lower wall thereof, is a throttle lever 12 extending upwardly through slots 13 and 14 formed in the partition and top wall, and connected by a wire 15 with the carburetor control valve of the engine. Rearward pivotal movement of the lever may result in opening the throttle valve for admitting fuel and increasing the speed of the engine and forward movement of the lever will reduce speed and tend to suspend operation of the engine.

Slidable in the channel is an actuator or plunger 16 adapted to be forced in the direction of the throttle lever by a spring 17 in the channel having one end bearing against a plug 18 closing the rear end of the channel and an opposite end bearing against the rear end of the plunger.

The plunger is notched to provide a stop shoulder 19 engageable by the upper end 20 of a plunger-locking switch bar 21 centrally pivottally mounted on a pin 22 set in the side walls of the casing, the tip extending through the slot in the partition to engage in the plunger notch, whereby the bar may lock the plunger in retracted position, and the plunger when released may move against the throttle lever and rock the bar to suspend ignition as later described. The pin and switch are in conductive relation to the casing.

The slots further accommodate a cocking pin 23 mounted in the front end of the plunger and extending downwardly into the chamber to engage the curved upper end of the switch bar, and whereby the plunger is retained in suitable position against rotation to present the notch therein downwardly and assure engagement of the nose of the switch bar with the stop wall of the plunger.

The switch bar is retained in plunger latching position by a releasing or latching lever 25 pivotal on a pin 26 mounted in the casing side walls and having a short front arm 27

provided with a squared tip engageable in a squared notch 28 formed in the lower end of the switch bar. A spring 29 comprising a wire mounted on a stud 30 fixed to the casing has opposite ends engaging respectively the lower face of the longitudinal ribs 6 and the rearwardly extending long arm of the latching lever 25 whereby the short arm of the lever is urged into bar latching position.

- 10 A wire or release cable 32 fastened to the outer free end of the longer arm of the latching lever extends through a bushing 33 mounted in mating grooves in the casing member and is provided with a ring 34 to which an 15 easily breakable string 35 may be fixed. The other end of the string may be attached to the wrist of the boatman whereby a slight pull on the string will result in tipping the latching lever and releasing the switch bar to 20 permit the spring-pressed plunger to move forward in the casing to shift the switch bar and operate the throttle lever.

The device may be easily adapted for controlling an ignition circuit in either battery 25 or magneto operated systems and is preferably adapted to be applied for use selectively with either of said systems.

For use in systems including a single magneto, a contact 37 mounted in one of the casing members, preferably the body member as 30 illustrated in Fig. 3, is connected to the circuit, and the switch bar when shifted by the plunger moves into conductive relation therewith for shorting the ignition circuit through 35 the casing members 3-4 and the wire 15. When two magnetos are in use, other contacts such as 38 may be provided for engagement by the bar to short the several circuits.

For battery circuits a contact 40 may be 40 provided in the casing in a suitable position for contact with the switch bar when the latter is in latched position as shown in Fig. 2, to close the circuit to the engine. The bar is thus adapted to swing away from the contact to break the circuit when released from the lever latch and moved by the plunger.

The contacts comprise pins mounted in insulating bushings in the casing, and having rounded heads protruding into the casing 50 chamber onto and from which the bar may slide easily.

A coil spring 41 is further preferably provided on the pin 22 between the bar and the cover to urge the switch bar into close conductive relation with the contacts.

The adaptation of the invention for use with apparatus including a battery ignition system as illustrated in Fig. 4, wherein a circuit grounded in the engine frame at 42 includes a timer 43, an ignition coil 44, a spark plug 45 connected to the coil, and a battery 46, a wire 47 leading to the contact 40, and the switch bar 21 is grounded in the casing 65 by the pin 22 as indicated at 48 for closing

the circuit through the lever 12 and wire 15 to the engine frame.

In using the device on a motor boat, the operator retracts the throttle lever and incidentally retracts the plunger, whereby the cocking pin swings the switch bar into position to permit the ignition system to operate, the switch bar latches the plunger and the releasing lever latches the switch bar. The throttle lever may then be operated to open and close the carburetor without disturbing the plunger or switch bar. Should the operator be thrown from the boat, the resulting pull on the string will cause release of the switch bar and permit the plunger to be moved forward by the spring to move the throttle lever toward a carburetor closing position and move the switch bar into position to suspend ignition.

What I claim and desire to secure by Letters Patent is:

1. In apparatus of the character described including a motor having an ignition circuit, and a throttle lever, a casing supporting said lever, a contact in said circuit mounted in the casing, a bar conductively connected with the casing and movable into and out of conductive relation with said contact, and bar latching means including a spring-pressed plunger controlled by said throttle lever and a pivoted latch controlling said plunger.

2. In combination with an engine, a throttle for controlling the speed of the engine, movable means for operating the throttle, and an ignition circuit for the engine, a switch for controlling said ignition circuit, means responsive to movement of the throttle operating means in one direction for setting the switch in position to render the circuit effective, a spring for moving said throttle responsive means in the opposite direction, means for restraining the said responsive means against tension of the spring, and means for releasing said restraining means.

3. In combination with an engine, a throttle for controlling the speed of the engine, and an ignition circuit for the engine, a switch for controlling the ignition circuit, means operating incidentally to initial opening movement of the throttle for actuating said switch to render the circuit effective, a spring tensioned upon movement of said operating means, means for latching said operating means against the tension of said spring, and means for releasing said operating means for closing said throttle and moving the switch to render the circuit ineffective.

4. In combination with an engine having a throttle and an ignition circuit, and a throttle lever for operating the throttle, a switch for controlling said circuit, means including a member operable by said throttle lever for setting the switch in position to

render the circuit effective, and means independent of said throttle lever and including said member for simultaneously moving the switch to render the circuit ineffective and closing the throttle.

5. In combination with an engine, a throttle for controlling speed of the engine, and an ignition circuit for the engine, a switch for controlling the ignition circuit, means

10 for actuating said switch to render the circuit effective incidental to opening movement of the throttle, and means independent of the throttle for simultaneously moving the switch and the throttle to stop operation of

15 the engine.

6. In combination with an engine, a throttle for controlling speed of the engine and an ignition circuit for the engine, a switch controlling the ignition circuit, means for

20 latching the switch in functional position on opening of the throttle, and means for releasing the latch to automatically move the switch to nonfunctional position to stop operation of the engine.

25 7. In combination with an engine, a throttle for controlling speed of the engine and an ignition circuit for the engine, a switch controlling the ignition circuit, means for latching the switch in functional position, including means operable to move the throttle, and means for releasing the latch to automatically move the switch and throttle to nonfunctional position to stop operation of

30 the engine.

35 8. In combination with an engine, a throttle lever, and an ignition circuit, a casing, means including a contact supported by the casing and connected to the circuit and a switch bar pivotally mounted on the casing

40 for movement into and out of engagement with said contact for controlling the circuit, a spring-pressed plunger engageable with said throttle lever and having a notch to receive said switch bar for latching the

45 plunger in retracted position, and means for latching the switch bar.

9. In a device of the character described, in combination with a vehicle and an engine mounted on the vehicle having a lever oper-

50 ated valve, a casing mounted on the vehicle, a spring pressed plunger slidable in the casing, a lever for operating said valve mounted on the casing and pivotal in the path of said plunger to retract the same against the in-

55 fluence of said spring and be pivotally moved thereby, and means for latching the plunger in retracted position.

10. In a device of the character described, including a support and an ignition circuit,

60 a contact mounted on the support and connected to the circuit, a switch movable into and out of engagement with said contact for controlling the circuit, means for moving the switch, a throttle lever pivoted on the

65 support and engageable by the switch mov-

ing means, means for latching the switch against the influence of said moving means, and means for releasing the latching means to release the switch moving means for actuating the throttle lever.

70 11. In apparatus of the character described including a circuit, a support, means including a contact mounted on the support and a switch pivotal on the support into and out of engagement with said contact for controlling the circuit, means including a spring pressed plunger slidable on the support for moving the switch, means including said switch for latching the plunger in retracted position, a throttle lever pivoted on the support to move the plunger into latching position, and a flexible cable operable to release the plunger to cause the plunger to operate the throttle lever.

75 12. In combination with an engine and an ignition circuit, a casing spaced from the engine, means including a contact supported by the casing and connected to the circuit and a switch bar pivotally mounted on the casing

80 for movement into and out of engagement with said contact for controlling the circuit, a spring-pressed plunger having a notch to engage said switch bar for latching the plunger in retracted position, a throttle lever mov-

85 able on the casing for retracting the plunger to engage said switch bar, a latching lever pivotally mounted on the casing to engage said bar for retaining the same in plunger-latching position, and means for moving said lever to release the bar for enabling the 100 plunger to move the bar and shift the throttle lever.

90 13. In combination with an engine and an ignition circuit, a casing spaced from the engine, means including a contact supported by the casing and connected to the circuit and a switch bar pivotally mounted on the casing

95 for movement into and out of engagement with said contact for controlling the circuit, a spring-pressed plunger having a notch to receive said switch bar for latching the plunger in retracted position, a throttle lever

100 pivoted to the casing and engageable with the plunger to retract the same, means for retaining the bar in plunger-latching position, and means including a cable supported by the casing for moving said latch to release the bar for enabling the plunger to move the bar and shift the throttle lever.

110 14. In combination with an engine, a throttle valve for controlling speed of the engine, and a lever for actuating the throttle valve, an actuator associated with the lever and rendered effective upon initial movement of the lever in opening the throttle valve, means

115 for latching the actuator in effective position, and means for releasing the latching means to cause the actuator to move the lever and close the throttle valve.

120 15. In combination with an engine and a

- throttle valve controlling speed of the engine, a lever for actuating the throttle valve, a spring-pressed actuator associated with the lever and movable thereby to tension the spring upon initial movement of the lever to open the throttle valve, means for latching the actuator against tension of its spring, and means for releasing said latching means to cause the actuator to close the throttle valve.
16. In combination with a vehicle and an engine mounted on the vehicle, a throttle valve controlling speed of the engine, a lever mounted on the vehicle and manually operable to actuate the throttle valve, a spring-pressed actuator associated with a lever to move the lever in a direction to close the throttle valve, means normally restraining the actuator against tension of its spring, and frangible means associated with said restraining means and adapted to be connected with an operator of the vehicle to permit the operator to release said actuator for automatically moving said throttle lever when the operator leaves the vehicle.
17. In combination with the throttle lever and an ignition switch of an engine, means for actuating the throttle and the switch comprising an actuator engageable with the throttle and the switch, means latching the actuator in retracted position, and means for releasing the latching means to cause the actuator to move the switch and throttle to stop operation of the engine.

In testimony whereof I affix my signature.
